H. S. MORTON,
SAFETY DEVICE FOR MOVING PICTURE MACHINES,
APPLICATION FILED AUG. 2, 1916.

1,230,201.

Patented June 19, 1917.

Inventor

Houston S. Morton,
By Edwin Guthrie,
Attorney.

UNITED STATES PATENT OFFICE.

HOUSTON S. MORTON, OF DETROIT, MICHIGAN.

SAFETY DEVICE FOR MOVING-PICTURE MACHINES.

1,230,201.

Specification of Letters Patent. Patented June 19, 1917.

Application filed August 2, 1916. Serial No. 112,813.

To all whom it may concern:

Be it known that I, HOUSTON S. MORTON, a citizen of the United States, residing at Detroit, in the county of Wayne and State of Michigan, have invented certain new and useful Improvements in Safety Devices for Moving-Picture Machines, of which the following is a specification.

This invention relates to safety devices for moving picture machines, and belongs to that class of contrivances for similar purposes, wherein a shutter or shield is caused to move into the path of the light from the lamp and between the lamp and the strip or film, when the picture strip or film is broken, or when the tension upon it is much slackened, or when by reason of derangement of the strip-feeding means or from any other accident the strip is drawn taut and stopped or much retarded in its movement.

The object of this invention is the production of parts having special construction and arrangement with respect to each other, by which it is believed a particularly dependable safety accessory apparatus is provided, that is simple in structure and prompt and effective in operation.

The accompanying drawings illustrate the form and disposition of the parts of this invention, and Figure 1 represents a side view of all the parts assembled. Fig. 2 is a side view, somewhat enlarged, of the strip-supporting roller and the pivoted hub or center, with various attached parts, and showing the circuit breaker controlling the electro-magnetic shield-operating contrivances, and the motor circuit. In this figure the insulating case containing the circuit breaker is shown in vertical section, and the figure is partly diagrammatic, representing the electrical connections and showing the front of the lamp with the shield raised. Fig. 3 is a vertical cross-section of the insulating casting, and shows the circuit breaker in detail. Throughout the description and drawings, the same letter is used to refer to the same part.

Upon a table A is placed the lamp B, controlled by the electric switch b. The lamp directs the light upon the strip C that passes from a container D to a receiving chamber E, through guiding devices e at the rear of the lens holder.

A suitable support F is erected upon the table, and a hub f is rotatively held thereon.

On one side there is connected with the hub,

an insulating block G, and an arm g is connected with the spindle of the hub or center. The insulating block G carries a metallic roller H, termed in this description the contact member, and, the arm g is formed into a fork h, in which is rotatively carried the main roller or film wheel J. The strip or film C passes around the roller J, as shown in Figs. 1 and 2, and thence around another roller j. The roller j is displaceable together with its bearing K. The bearing is located in a suitable slot K' in the table A, and it is yieldingly held therein by means of the flat spring k, best shown in Fig. 2.

In the circuit breaker, there are four contact fingers, L, M, l and m, and the contact member H affords a metallic connection between the fingers L and M, thus closing the electric circuit leading to the shield magnet, and, the member H also closes the circuit represented by the conductors N and n, that lead to the motor for running the film strip. The motor and connections are not shown, as they form no part of this invention.

From the fingers L and M the wires O and P lead by way of the battery Q, or other source of electric current, to the shield-supporting electro-magnet R. The armature r of the magnet is attached to the shield or shutter S, that is movable up and down in grooves s in the vertical posts a standing upon the table A.

In the operation of this invention, let it be assumed that the film strip C suddenly breaks. It is believed to be made clear from the drawings and the foregoing explanation that the roller J would fall, and the contact member H would be moved upwardly free from the fingers of the circuit breaker. The magnet R would no longer support the shield which would fall and shut off the light from the strip thus preventing the strip from taking fire, and, at the same time, the motor circuit N, n would be interrupted bringing the machine to rest. In the usual manner, and as a matter of precaution, the circuit breaker is inclosed in an insulating box or casing T.

Let it be now supposed that by reason of some accident the strip should be held so that it could not be drawn freely about the roller J into the receiving chamber E. That condition would, as will be readily understood, exert a pull upon the roller J, overcoming the flat spring k, and up-setting the bearing K thereby drawing the roller

j out from beneath the roller J, which would drop with the result already explained. In either case the action is very prompt and certain, and the construction is believed to be of such simple character as to almost never get out of order.

Having now described this invention, and explained the mode of its operation, what I claim is:

- 10 1. In a safety device for moving picture machines, the combination with a lamp, of a film, a shutter movable between the lamp and film, a roller supported by the film, means actuated by the falling of the said roller for operating the shutter, a guide roller arranged below the said film-supported roller, the said film passing under the said film-supported roller and around the said guide roller, and a displaceable bearing for the guide roller whereby excessive strain upon the film draws the guide roller from beneath the film-supported roller allowing the same to fall.
- 15 2. In a safety device for moving picture machines, the combination with a lamp, of a film, a shutter movable between the lamp and film, a roller supported by the film, an electric switch operated by the falling of the roller, electro-magnetic means controlled

by the said switch for operating the said shutter, a guide roller arranged below the said film-supported roller, the said film passing under the said film-supported roller and around the said guide roller, and a displaceable bearing for the guide roller whereby excessive strain upon the film draws the guide roller from beneath the said film-supported roller and allows the same to fall.

- 20 3. In a safety device for moving picture machines, the combination with a lamp, of a film, a shutter movable between the lamp and film, a roller supported by the film, means actuated by the falling of the said roller for operating the shutter, a guide roller arranged below the said film-supported roller, the said film passing under the said film-supported roller and around the said guide roller, a support, a slot in the said support, a bearing for the guide roller removably seated in the said slot, and a spring acting upon the said bearing for holding the same yieldingly in the said slot whereby an excessive strain upon the film draws the bearing from the slot and the guide roller from beneath the film-supported roller allowing the same to fall.

In testimony whereof I affix my signature.

HOUSTON S. MORTON.
